Patented Apr. 20, 1965

200,894

COFFEE DISPENSER

John P. Sohn and Robert E. Little, Columbus, Ind., assignors to Arvin Industries, Inc., Columbus, Ind., a corporation of Indiana

Filed Dec. 18, 1963, Ser. No. 77,847

Term of patent 14 years

(Cl. D2—3)

FIG. 2.

FIG. 1 is a front elevation of a coffee dispenser showing our new design;

FIG. 2 is a rear elevation thereof;

FIG. 3 is a side elevation thereof;

FIG. 4 is a plan view thereof; and

FIG. 5 is a sectional view thereof taken on the line 5—5 of FIG. 1.

The undisclosed side of the coffee dispenser is a mirror image of the side shown.

We claim:

The ornamental design for a coffee dispenser, as shown and described.
